(57) **CLAIM**

The ornamental design for a “lucky chip,” as shown and described.

DESCRIPTION

FIG. 1 is a top perspective view of the lucky chip of the subject invention;

FIG. 2 is a plan view thereof;

FIG. 3 is a bottom view thereof;

FIG. 4 is a side view thereof; and,

FIG. 5 is a bottom perspective view thereof.

The broken line showing of the indicia is for illustrative purposes only, and forms no part of the claimed design.
